MERCURY VAPOR CURRENT CONVERTER

Herman Mees, Lodelinsart, Belgium, assignor to
Ateliers de Constructions Electriques de Char-
leroi, Brussels, Belgium, a firm of Belgium

Application July 10, 1946, Serial No. 682,535
In France July 19, 1945

11 Claims. (Cl. 250—27.5)

1

In certain installations for converting alternating current into direct current, intended for instance for feeding electrolysis installations with a current capacity of the order of several tens of thousands of amperes, use may conceivably be made of mercury vapor current converters of high unitary power. The total power to be supplied can thus be assured by several poly-anodic converters with a large number of anodes.

The design and construction of such converters present various difficulties. If a normal central cathode analogous to that employed on converters of medium power is used, the relative position of the anodes and the cathode is such that the value of the drop in voltage in the arc increases in an appreciable manner and is no longer compatible with an economical converter yield.

In order to reduce the distance which separates the anodes from the cathode, an annular cathode of large diameter placed in such a way that its relative position with regard to the anode renders it possible to shorten the path of the arc may be provided, while retaining a sufficient operating safety against the risk of backfiring.

Moreover, the operation of the heavy poly-anodic converters may be complicated by a zone of high mercury vapor pressure developing around the cathode, an excess pressure which under certain conditions entails the elimination of the valve effect of the converter.

This high mercury vapor pressure is influenced by the intensity of the cooling of the walls of the converter on the one hand, and on the other hand by the distance which separates these walls from the cathodic high pressure zone. In metal tank converters of great power the distance between these two elements may be such that the cooling of the walls has no effect on this high pressure mercury vapor cathodic zone; it is no longer possible, by acting on the cooling of the walls alone, to reduce the mercury vapor pressure in the immediate vicinity of the cathode.

It has already been proposed, in the case of annular cathodes, to arrange a tubular cooling member traversing the interior of the converter tank from the space comprised in the center of the annular cathode to the anode-carrying lid. This arrangement, while it may permit of an effective cooling of the mercury vapor high pressure cathodic zone, presents on the other hand great difficulties of execution, especially that of a vacuum-proof joint at the cathode or at the anode-carrying lid, capable of making up for the expansion differences between the tubular network and the balance of the metallic tank of the converter.

The solutions heretofore suggested have not given a really practical solution to the problem

2

of a mercury vapor current converter for very high power magnitudes.

The present invention relates to a new arrangement of a mercury vapor converter with metal vat or tank for very high power magnitudes, characterized in that, in addition to providing an arrangement particularly adapted to reduce the value of the voltage drop in the arc and to prevent the formation of a cathodic region of high mercury vapor pressure capable of eliminating the valve effect of the converter, it also provides a facility and simplicity of construction which call for no special mounting or executing device.

To this end, there is arranged at the bottom of the metallic vat or tank of the converter an annular cathode of large diameter and with a small mercury volume and including but one packing joint with the tank, and on the inside of this tank a central cooling device made up wholly or in part of a tubular bundle, freely suspended from the anode-carrying lid of the converter and traversed by a cooling fluid, for example air.

The annular cathode is characterized by the fact that its effective section is limited on its outer side by a single or multiple ring of insulating and refractory material, such as quartz for instance, in a manner analogous to that used for conventional central cathodes.

It is moreover characterized by the fact that its central portion is covered by a cup of insulating and refractory material such as quartz, placed over its concave surface and thus restricting, towards the center of the cathode, the effective section of the latter and the expansion region of the cathodic spot.

The assembly of the rings and of the cup delimiting the active region of the annular cathode is placed on a metal cathode bottom of large diameter and conventional construction, as for central cathodes. The expansion of the mercury towards the center of the cathode is limited by a core or a crown of metal added to the metal bottom of the cathode.

The cathode thus made up can be joined at the bottom of the metallic tank of the converter by a single packing joint which does not require special precautions such as are called for by the double joint of a normal annular cathode. As a matter of fact, no measure has to be taken to insure the simultaneous tightness of two flat concentric joints which may or may not be located on the same plane; moreover, no arrangement of elastic joint needs to be provided as in the case of the central cooling device traversing the tank assembly of the converter from the cathode bottom on the inside of the annular cathode to the anode-carrying lid.

A normal central cathode construction can

therefore be applied to an annular cathode of large diameter of this type, with the particularly attractive advantage of the reduction of the length of the arc, thus making it possible to obtain in a tank of large dimensions a drop in voltage in the arc comprised between admissible values, practically independent of the general dimensions of the converter and solely a function of the relative position of the cathode with respect to the anode.

On the attached sheet of drawing, Fig. 1 diagrammatically shows, by way of a non-restrictive example, a view in section of a presently-preferred embodiment of a mercury vapor current converter of very high power according to the invention. Every detail not indispensable to the understanding of the invention has for the sake of clarity, been omitted.

Fig. 2 is a view of a modified detail.

The metallic tank C of the converter is provided at its upper end with an anode-carrying lip P—the anodes being shown at A—and at its lower end with a cathode K. A jacket G encompasses the tank C, as shown, and the intermediate space, coextensive with the peripheral extent of the wall of the tank and with its conical bottom, may house cooling means in the form of conduits of any suitable cross section. Alternatively, and as shown, cooling baffles m may be provided extending over the entire peripheral surface of tank C and over its conical bottom. A cooling fluid such as air may be blown through the aforesaid intermediate space, use being made for this purpose of any suitable circulating device such as a blower, fan, pump or the like (not shown). The stream of cooling fluid, flowing by in contact with baffles m, withdraws heat transmitted therethrough.

The cathode K is made up of a sheet metal plate p constituting the bottom of the cathode and can be cooled by suitable means, such as baffles or vanes x. In its central portion, the cathode is provided with a core n for limiting the extent of the mercury.

The extent of the cathode may be limited toward the outside, for instance by a quartz ring a of a shape similar to that of the outer rings of conventional central cathodes. Toward the center, this extent is limited by a quartz cup a' positioned with its open side down, as shown, and covering the central metal core n. The cup a' thus prevents the cathodic action from becoming localized at the central metal part of the cathode and renders possible the free return to the cathode of the liquid mercury droplets which are condensed on its convex surface.

The entire cathode assembly thus constituted is fixed to the bottom of the tank C of the converter by a conventional central cathode joint j, for example of the type with an intermediate annulus.

The relative position of the cathode and the anodes may be identical to that of a central cathode converter with a low voltage drop in the arc, so that the drop in voltage of the arc of the annular cathodic converter remains of the same order of magnitude notwithstanding the greater number of anodes united in one and the same tank and, consequently, in spite of the greater unitary power of the converter.

In the illustrated embodiment, in order to reduce the distance between the high-mercury-vapor section (above the cathode) and the cooling means, in this case the means m on the periphery of the wall and conical bottom of tank C of the

converter, a bundle of tubes T is arranged, in freely suspended manner, on the anode-carrying lid P, the tubes T depending down into the mercury vapor high pressure cathodic region.

5 The tubes T terminate in a single tubular return conduit R which is likewise suspended from lid P and which houses the electrically-driven fan V supported from spider w. The fan V sets the cooling air into motion. A cup-shaped baffle 10 member e, arranged as shown on the drawing, directs the air to the fan blades. Each tube of the bundle T is thus traversed by air set into motion in this manner, so that from the several inlets e to the several outlets s there is a flow 15 in parallel of a plurality of streams of air. The inlets e of the tubes and the outlet g of the central return conduit R for the air are disposed in adjacent portions of the anode-carrying lid P.

In this way the cooling action is brought directly to the inside of the mercury vapor high pressure cathodic zone.

The number of tubes comprising the tube bundles may, of course, be varied, the number being shown on the drawing being merely illustrative. The downward extent of the several tubes, the configuration of which as shown is preferably L-shaped in character, is such that the high pressure region is penetrated thereby. The L-configuration may be varied, however, and the tubes may for example be incurved toward the high pressure mercury vapor pressure region, as shown for example in the detail of Fig. 2, so as to increase the influence of the cooling on the latter.

35 The cooling tubes T may, if desired, be arranged in series with the cooling device m, whereby a common source of power—fan, blower or the like—may be used for circulating fluid through both cooling arrangements. The circulation is 40 established so that the cooling fluid circulates from the top of the tank toward the cathode.

The diameter of the tubes T is not critical and may be varied within considerable limits. The tubes are preferably made of metal.

45 The cooling device for the high pressure mercury vapor cathodic zone, realized by the present invention, therefore presents, with relation to prior arrangements, the double advantage of a complete cooling efficacy for the high pressure zone, combined with a simplicity of construction perfectly adaptable to the metallic tanks of converters of current construction.

Having thus disclosed the invention, what is claimed is:

55 1. In a high-power mercury vapor current converter, a metallic tank, an anode on said tank, a mercury cathode contacting the metallic bottom of said tank, means for limiting the outward extent of said cathode, and means for limiting the inward extent of said cathode, whereby the zone of high mercury vapor pressure which tends to be established above said cathode is commensurately circumscribed.

65 2. In a high-power mercury vapor current converter, a metallic tank, an anode on said tank, a mercury cathode on the metallic bottom of said tank, means for limiting the outward extent of said cathode, means for limiting the inward extent of said cathode, whereby the zone of high mercury vapor pressure which tends to be established above said cathode is commensurately circumscribed, and cooling means freely suspended from said lid and extending downwardly into said zone whereby the said tendency

to establish a high pressure in said zone is minimized.

3. In a high-power mercury vapor current converter, a metallic tank, an anode on said tank, a mercury cathode on the metallic bottom of said tank, means for limiting the outward extent of said cathode, and means for limiting the inward extent of said cathode, whereby the zone of high mercury vapor pressure which tends to be established above said cathode is commensurately circumscribed, said first-named means comprising a refractory insulating ring encompassing the outer portion of said cathode.

4. In a high-power mercury vapor current converter, a metallic tank, an anode on said tank, a mercury cathode on the bottom of said tank, means for limiting the outward extent of said cathode, and means for limiting the inward extent of said cathode, whereby the zone of high mercury vapor pressure which tends to be established above said cathode is commensurately circumscribed, said second-named means comprising a centrally located metallic core and a cup of insulating and refractory material covering said core.

5. In a high-power mercury vapor current converter, a metallic tank, an anode on said tank, a mercury cathode on the metallic bottom of said tank, means for limiting the outward extent of said cathode, and means for limiting the inward extent of said cathode, whereby the zone of high mercury vapor pressure which tends to be established above said cathode is commensurately circumscribed, and means including a single annular sealed joint for connecting said bottom to said tank.

6. In a high-power mercury vapor current converter, a metallic tank, a mercury cathode at the bottom of the tank, means for restricting the outward and inward extent of said cathode, whereby a corresponding zone of high mercury vapor pressure tends to be established above said cathode, an anode-carrying lid on said tank, said cathode and anodes being symmetrically arranged with respect to the central axis of said tank, a tubular bundle freely suspended from said lid and extending downwardly into the said zone, and means for circulating cooling fluid through said bundle, whereby the tendency to build up high pressure in said zone is minimized.

7. In a high-power mercury vapor current converter, a metallic tank, a mercury cathode on the bottom of the tank, means for restricting the outward and inward extent of said cathode, whereby a correspondingly restricted zone of high mercury vapor pressure tends to be established above said cathode, an anode-carrying lid on said tank, a tubular bundle freely suspended from said lid and extending downwardly into the said zone, and means for circulating cooling fluid through said bundle, whereby the tendency to build up high pressure in said zone is minimized, the inlets to and outlets from said tubular bundle being disposed in adjacent portions of said lid, and said cathode and anodes being symmetrically arranged with respect to the central axis of said tank.

8. In a high-power mercury vapor current converter, a metallic tank, a cathode at the bottom of said tank, whereby a zone of high mercury vapor pressure tends to be established above said cathode, an anode-carrying lid on said tank, a tubular bundle freely suspended from said lid and extending downwardly into the said zone,

means for circulating cooling fluid through said bundle, whereby the tendency to build up high pressure in said zone is minimized, said tubular bundle comprising a plurality of substantially L-shaped conduits whereby a plurality of streams of cooling fluid traverse said conduits in parallel, and a tubular shaft common to said conduits and constituting an outlet passage for said streams.

9. In a high-power mercury vapor current converter, a metallic tank, a cathode at the bottom of said tank, whereby a zone of high mercury vapor pressure tends to be established above said cathode, an anode-carrying lid on said tank, a tubular bundle freely suspended from said lid and extending downwardly into the said zone, means for circulating cooling fluid through said bundle, whereby the tendency to build up high pressure in said zone is minimized, said tubular bundle comprising a plurality of substantially L-shaped conduits whereby a plurality of streams of cooling fluid traverse said conduits in parallel, a tubular shaft common to said conduits and constituting an outlet passage for said streams, and means for instigating said streams disposed in said tubular shaft.

10. In a high-power mercury vapor current converter, a metallic tank, a cathode at the bottom of said tank, whereby a zone of high mercury vapor pressure tends to be established above said cathode, an anode-carrying lid on said tank, a tubular bundle freely suspended from said lid and extending downwardly into the said zone, means for circulating cooling fluid through said bundle, whereby the tendency to build up high pressure in said zone is minimized, said tubular bundle comprising a plurality of substantially L-shaped conduits whereby a plurality of streams of cooling fluid traverse said conduits in parallel, and a tubular shaft common to said conduits and constituting an outlet passage for said streams, each said conduit having a portion curved into said zone.

11. In a high-power mercury vapor current converter, a metallic tank, a cathode at the bottom of said tank, whereby a zone of high mercury vapor pressure tends to be established above said cathode, an anode-carrying lid on said tank, cooling means freely suspended from said lid and extending downwardly into the said zone whereby the tendency to build up high pressure in said zone is minimized, a tubular outlet shaft mounted on said lid and in which said cooling means terminate, a cooling jacket about said tank, and means for producing a stream of cooling fluid through said cooling jacket, through said cooling means and out through said outlet shaft.
